UNITED STATES PATENT OFFICE.

LANVILLE A. BROWN, OF KANSAS CITY, MISSOURI, ASSIGNOR TO BROWN DETACHABLE DISAPPEARING BED COMPANY, OF KANSAS CITY, MISSOURI.

DETACHABLE DISAPPEARING BED.

1,290,893.

Specification of Letters Patent.

Patented Jan. 14, 1919.

Application filed August 12, 1915. - Serial No. 45,134.

To all whom it may concern:

Be it known that I, LANVILLE A. BROWN, a citizen of the United States, residing at Kansas City, in the county of Jackson and State of Missouri, have invented certain new and useful Improvements in Detachable Disappearing Beds, of which the following is a full, clear, and exact description, such as will enable others skilled in the art to 10 which it appertains to make and use the same.

The invention relates to disappearing beds and seeks to provide a simple and efficient form of bed which may when not in use be folded and stored within a small inclosure as the ordinary closet.

Disappearing beds are usually attached to the inclosure that is employed to conceal them when not in use, and can only be occupied adjacent the inclosure which is often in a very undesirable part of the room for sleeping purposes.

It is essential that disappearing beds be so constructed that they may be automatically detached from the concealing inclosure and easily moved to any desirable location in the room, and as easily returned and automatically attached to the inclosure when not employed by the occupants. In order to 25 accomplish the foregoing it is necessary to provide a suitable folding frame with a minimum weight and maximum strength so that it will be dependable when occupied, and require a slight exertion to fold and unfold and to move the bed to and fro.

The present invention seeks to provide an improved disappearing bed with a folding frame.

A further object of the invention is to 30 provide an expanding and contracting wheel base which will automatically extend as the frame is unfolded and retract with the folding of the frame.

A still further object of the invention is 35 to balance the folding parts with springs so connected as to balance the folding parts approximately equally throughout the entire sweep of the folding or unfolding movement thereof, thereby eliminating the heavy

weights usually employed for balancing folding beds. 50

A still further object of the invention is to provide an improved form of folding support for the overhanging end of the principal folding member. 55

A still further object is to provide an improved safety latch to prevent the frame from closing while occupied.

With these and other objects in view the invention consists in the improved features 60 of construction, shapes, combinations and arrangements of parts hereinafter set forth and more particularly pointed out in the appended claims, the improvements being illustrated by the accompanying drawings. 65

In the drawings:—

Figure 1 is a perspective view of the improved bed detached from the inclosing structure and unfolded, the springs not being illustrated because of common and well known construction. 70

Fig. 2 is a perspective view of the bed folded, and a fragmentary view of the exterior of the inclosing structure, also the track to engage and guide the bed as it is 75 inclosed.

Figs. 3 to 8 inclusive are enlarged.

Fig. 3 is a fragmentary view of the bed illustrating the mechanism of the expanding and retracting wheel base the inclosing 80 easement thereof being broken away.

Fig. 4 is a fragmentary sectional view taken on line *a—a* of Fig. 3.

Fig. 5 is a fragmentary view of the safety latch the frame being broken away. 85

Fig. 6 is a fragmentary view of the folding support for the overhanging end of the main folding member, with the support unfolded.

Fig. 7 is the same view as that of Fig. 6 only with the support folded. 90

Fig. 8 is a sectional view taken on line *b—b* of Fig. 6.

The end or head piece posts 1 are preferably of thin metal tubing and square, and are joined by the round metal tubes 2, the latter tubes being connected by the round metal tubes 3. The intermediate posts 4 are of the same material and shape as the

posts 1, and are rigidly connected thereto by the members 5 and 6, which are also thin square metal tubing, the members 6 being connected by the angle shaped bar 7 to stiffen the frame work of the head piece which consists of all of the posts and tubes hereinbefore described.

To the members 5 are pivoted by sleeves 8, balls 9 and sockets 10, the longitudinal 10 spring frame members 11, the sockets being rigid with the members 5, the ends 12 of the members 11 having rigidly secured thereto the arms 13, which extend outward and upward from the ends of the members and 15 have connected thereto the transverse spring frame member 14, the latter being an ordinary angular shaped bar with holes 15 therein in which the springs 16 are looped, the springs not being shown because of well 20 known construction.

To the ends 17 of the spring members 11 are rigidly connected the arms 18 which are connected by the angular shaped bar 19 forming an end member of the spring frame 25 and provided with the holes 20 for the connection of the springs 16, which are shown connected to the member and broken away to more fully illustrate the frame structure.

Mounted on the end spring members 19 30 are flanges 21 to which is secured the tube forming the end posts 23 and upper rail 24 of the foot piece, the posts 23 being connected by the lower foot piece rail 25 and the latter and the upper rail 24 being connected by the vertical tubes 26, and completing the upper portion of the foot piece.

The arms 18 are provided with the hubs 27, and an annular flange 28 extending from 29 to 30, the latter having two notches 31 40 and 32 therein, the flanged end 33 of the leg 34 having an elongated hole or slot 35 which fits over the hub 27, and a tooth being engaged in the notch 31 in Fig. 6, and in the notch 32 as shown in Fig. 7, the former position showing the leg extended downward while in the latter position the leg is shown folded. The flanged end 33 is held in position by the washer 37 and screw bolt 38, the coil expansion spring 39 connecting from 45 the bolt to the lug 40 on the leg 34 holding the tooth 36 in position in the notch and holding the leg in either position as desired.

The legs 34 are connected by the tube 41 and when it is desired to change the position 50 of the legs it is only necessary to pull the legs in a direction away from the hubs 27, which may be done by taking hold of the tube 41.

Near the outer ends of the end spring 55 frame 11 are connected the coiled expansion springs 42 the opposite ends of the springs being connected to the angle shaped bar 7 and near the center thereof, so that the springs will exert opposing angular

lines of force and so that they will be in 65 tension during the entire sweep of the folding of the spring frame from the position shown in Fig. 1 to that of Fig. 2, and so the springs will have a gradually diminishing force as the spring frame is folded, it being 70 obvious that more force is required to counterbalance the overhanging weight of the frame when in the position shown in Fig. 1 than when in the position shown in Fig. 2, the springs being of a strength that will 75 nearly balance the frame so that a very slight exertion will fold the frame and so that a small force will resist the unfolding weight of the frame, the springs making the spring frame easy to fold or unfold. 80

The bedding is usually resting on the springs and folded with the frame, the bedding not being illustrated because of common and well known construction.

Secured to the lower tube 2 and curving 85 downward and inward and connecting to the angle shaped bar 7 is the toothed quadrant 43 which is engaged by the safety latch 44 when the frame is unfolded as in Fig. 1, to prevent the frame from closing up until it is desired to close it, the latch being pivoted at 45 to the bar 14, and having the spring 46 arranged to hold it in engagement with the quadrant. The latch has secured thereto the wire 47 which passes through the end members 14 and 20 and is provided with the ring 48 at the opposite terminal for the purpose of disengaging the latch when it is desired to fold the frame from the position of Fig. 1 to that of Fig. 2. 90

Secured to the frame members 6 are the guides 49 in which are fitted to slide freely to and fro the rack bars 50, the bars being smooth on the bottom edge 51 and having teeth 52 in the upper edge, the gear wheels 19 95 and 54 being journaled on the pin 55, the latter being supported and secured in position by the plates 56 and 57.

The gear wheel 58 is journaled on the shaft 59 also supported by the plates 56 and 11 57 and serves as a roller to receive the upward thrust of the rack caused by any upward strain on the end post 60, the roller 61 being located below the rack bar and journaled on the pin 62, the latter projecting 11 from the bracket 63 which is secured to the member 6, the roller serving to resist any downward thrust caused by the upward thrust on the post 60 fulcrumed on the gear wheel 58 so that the rack bar will play to 12 and fro freely without friction even though the post 60 support considerable weight.

Projecting from the sleeve 8 is the arm 64 shown integral with the sleeve, and integral with the arm is the segmental gear 65 12 which is positioned to engage the gear 53, the gears 53 and 54 being secured together and the gear wheel 54 meshing with the

teeth 52 of the rack bar 50 so that any movement of the frame that will tend to fold or unfold it will cause the rack bar to traverse the guides 49.

6 It will be noticed that the gear 53 is smaller than the gear 59 so that the rack bars 50 will have considerable more travel than if the gears were of the same dimension, the object being to produce a bed with 10 a narrow face when folded so that it will enter a narrow door, and to project the bars 50 a considerable distance when the spring frame is lowered so that the bed will stand safely and not fold up by the head piece 15 falling upon the spring frame which would be dangerous.

When the frame is unfolded from the position of Fig. 2 to that of Fig. 1 the rack bars 50 and posts 60 are extended and provide a much wider base for the head piece so 20 that it will have no tendency to close up, or fall upon the spring frame, and when the frame is folded the rack bars and posts are retracted forming a narrow base for the head 25 piece so that the entire bed when folded may be passed through the ordinary door as the door 66 and into an ordinary closet or inclosure as 67.

The posts 1, 4 and 60 and the legs 34 are 30 each provided with the ordinary caster wheels 68 so that the entire bed is easily moved along the floor whether folded or unfolded, it being obvious that when the bed is detached from the inclosure and unfolded 35 it may be moved about as the ordinary bed.

It is obvious that the gear wheels may be made of a ratio that will give the rack bars any desired amount of travel, and a change of the ratio of gears would not involve in 40 vention.

It is obvious that numerous changes may be made in the details as set forth without departure from the essentials of the invention.

45 What I claim as new, and desire to secure by Letters Patent, is:—

1. In a detachable disappearing bed, a pair of head piece posts suitably connected together, a pair of foot posts suitably connected 50 together, a pair of intermediate posts, a pair of longitudinally disposed members connecting each of said intermediate posts to the adjacent head piece post, a spring frame pivoted to the uppermost of each of said 55 pair of longitudinally disposed members and connecting to said foot posts, a pair of plates connecting each pair of said longitudinally disposed members, a shaft secured transversely between each pair of said 60 plates, a pair of revoluble gears on each of said shafts, a gear tooth quadrant mounted on each side rail of said spring frame, said quadrant in a circumferential line whose axis is approximately in the same axial line

as the pivoted connections of said spring 65 frame to said longitudinal members, said quadrant contained between said plates and the gear teeth thereof meshing with one of said gears, an extension bar slidably connecting to each of said lower longitudinally 70 disposed members, gear teeth in each of said extension bars, a post adapted to run on the floor on each of said extension bars, and the remaining gear of each of said pair of gears meshing in the companion extension 75 bar.

2. In a detachable disappearing bed, a head piece comprising head posts and intermediate posts, a pair of longitudinal members connecting each of said head posts to the 80 adjacent intermediate post, a spring frame pivoted to the uppermost of each of said pair of longitudinal members, a pair of plates connecting each pair of said longitudinal members, a gear toothed quadrant secured to 85 each of the side rails of said spring frame, said quadrants each positioned between the adjacent pair of plates, an extension bar slidably connected to each of the lowermost of said longitudinal members, a post on the 90 extensible end of each of said extension bars adapted to run on the floor and be extended forwardly as the spring frame is lowered, gear teeth in each of said extension bars, and geared connections mounted between 95 each of said pair of plates and connecting the adjacent gear toothed quadrant and extension bar.

3. In a detachable disappearing bed, a head piece comprising head posts and intermediate posts, a pair of longitudinal members connecting each of said head posts to the adjacent intermediate post, a transverse bar located higher than the uppermost of said longitudinal members and connecting said 100 head posts, an angle shaped bar underneath the lowermost of said longitudinal members, said bar connected to said longitudinal members adjacent said intermediate posts, a quadrant shaped bar connecting to approximately 105 the center of the bar connecting said head posts and to approximately the center of said angle shaped bar, teeth on said bar with the points thereof projecting upward, a spring frame pivoted to the uppermost of 110 said longitudinal members, the end of said spring frame adjacent said head posts projecting upwardly above said uppermost longitudinal members, springs to assist in folding said frame connecting said angle shaped 115 bar with the head of said frame, and a latch on said spring frame to engage said teeth and oppose the folding of said spring frame.

4. In a detachable disappearing bed, a suitable head piece, a spring frame pivoted 120 to said head piece, a quadrant shape bar secured to said head piece and spaced away from the axis of the pivotal connections of

4
said spring frame to said head piece, teeth in
said bar projecting in the direction of the
axis of said pivotal connections, said teeth
being in the form of ratchet teeth, springs to
assist in folding said frame connecting said
angle shaped bar with the head of said
frame, and a releasable latch on said spring
frame so positioned as to engage said teeth
and oppose the folding of said spring frame

and not oppose the lowering of said spring 10
frame.

In testimony whereof I affix my signature
in the presence of two witnesses.

LANVILLE A. BROWN.
